UNITED STATES PATENT OFFICE.

ROBERT H. HASSSLER, OF INDIANAPOLIS, INDIANA.

RADIUS-ROD ATTACHMENT MEANS.

1,164,618.

Specification of Letters Patent. Patented Dec. 14, 1915.

Application filed April 26, 1915. Serial No. 24,128.

To all whom it may concern:

Be it known that I, ROBERT H. HASSSLER, a citizen of the United States, residing at Indianapolis, in the county of Marion and

5 State of Indiana, have invented certain new and useful Improvements in Radius-Rod Attachment Means, of which the following is a specification.

This invention relates to chassis construction for automobiles, trucks and the like, and has special reference to radius-rod end supports where the rod is attached to the axle and also to the frame.

10 The object is to provide a strong and durable attachment and support for the radius-rod which will be at the same time elastic as to end thrust, lateral movement or torsional strain, whereby the vehicle will be easier riding and less liable to damage on rough 15 roads or in turning corners or rounding curves rapidly.

I accomplish the objects of the invention by the mechanism and means illustrated in the accompanying drawings, in which—

25 Figure 1 is a top plan view of a chassis for an automobile embodying my invention and showing parts sectioned adjacent the propeller shaft for purposes of clearer illustration. Fig. 2, is a section longitudinally 30 of the radius-rod through the support which connects an end of the rod with the rear axle, the view being on a larger scale than that of Fig. 1. Fig. 3, is a section on the line 3—3 of Fig. 2. Fig. 4, is a view similar 35 to Fig. 2, showing the displacement of the spring under an end thrust of the radius-rod. Fig. 5, the same under a swinging displacement of the rod. Fig. 6, is a view in front elevation of one end of the front axle 40 with the casing for supporting the radius-rod attached, and in partial section,—the spring and rod not being shown. Fig. 7, is a horizontal section longitudinally of the radius-rod of a modification wherein the 45 spring-bearing disks on the rod are more extended and the outer one is elastically held to the spring, and Fig. 8 is a modification wherein the outer coil of the spring is fastened to a tubular rod and the spring supported from its center coil.

Like characters of reference indicate like parts throughout the several views of the drawings.

50 By way of illustration I have shown my invention applied, in Fig. 1, to the chassis of an automobile, but desire that it be clearly

understood that it is not my desire nor intention to limit the application of my device to the form and arrangement of associated parts here shown.

60 Referring particularly to Fig. 1, 8 are the wheels, 9 the front axle, 10 the rear axle tube, 11 the main frame, 12 a leaf spring connecting the front axle with the frame, 13, 13, a pair of leaf springs connecting the rear axle 65 with the frame; 14, 14, inside brackets on the frame on the ends of which a fork 15 for supporting a propeller-tube 16, is pivotally mounted. The propeller shaft tube 16 is rigidly secured to the casing 17 which contains the usual differential gears, and it has longitudinal adjustment in the sleeve of the fork between the collars 18, 18. A propeller shaft 19 is mounted in the tube 16, and is splined with sliding adjustment in 70 the sleeve of a universal joint 20, which in turn is coupled to a crank shaft 21 of a propelling engine (not shown). The necessary adjustment between the crank shaft, mounted on the main frame, and the rear axle 75 80 which is connected with the frame by the leaf springs 13, 13, is thus afforded.

It is also desirable to provide radius- or brace-rods from the frame to both axles, with an adjustment to allow for variable 85 distances between said parts due to the spring connections between them; which adjustment should be elastically controlled to reduce the jar and strain on the vehicle. I have shown four of said radius-rods 22 in 90 Fig. 1 of the drawings, but a greater or less number may be employed according to the requirements. Each rod will be provided near each of its ends with an annular enlargement 23, (see Figs. 2, 4, 5 and 7), here 95 shown as integral with the rod, but which obviously might be a removable member slipped over a reduced outer portion of the rod and held by a shoulder formed by said reduced diameter. The extreme rod-end is 100 screw threaded as shown, and this threaded end is passed through the innermost coil of a volute spring 24, where it is held against the enlargement 23, by a washer 25, and a nut 26, the latter being preferably castellated 105 as shown and screwing on the threaded end of the rod. The corners of the enlargement 23 and of the washer 25, are rounded or chamfered next to the spring to avoid interference there with the spring at certain 110 adjustments of the rod.

The spring 24 is supported by an annular

casing 27 which has an inside channel 28 in which the outer coil of the spring is seated, the casing being split, as shown, to facilitate the assembly. For attachment to the front axle, 5 from which it is suspended, and to the frame to the side of which it is fastened, I provide an extension 29, from the casing with perforated lateral members through which perforations bolts 30 are passed and the casings 10 made fast in the manner shown.

For attachment of the casing 27 to the rear axle tube I form it with a collar-extension 31 (see Figs. 2, 3, 4 and 5) which is slipped on over the end of the tube and is 15 held in place by a set screw or other suitable means.

In the modification shown in Fig. 7, the range of adjustment between the rod and casing is limited by extensions 33 of the 20 peripheries of the members 23 and 25, and an adjustment longitudinally of the rod of the outer washer is provided for automatically by the action of a spring 35, interposed between the washer and the nut. This 25 affords an additional resiliency for resisting the end-thrust of the rod.

In the modification shown in Fig. 8, the radius-rod is tubular and has an expanded end 36 which is internally channeled and 30 forms a seat in which the helical spring 24 is seated. The support for the spring, here shown as a hanger 37 suspended from the rear axle, is fastened to the middle coil of the spring by a stub-shaft 38 passed through 35 the coil and held by a washer 39 and collar 40 pinned to the shaft instead of being screwed thereon.

In some applications in practice the above-described spring-support is only used for 40 one end of the radius-rod, the other end being fastened in more or less fixed manner to the frame or to the axle.

The operation of my elastic support will be readily understood from the drawings: For an end movement of the radius-rod the 45 spring will give toward either side of the volute in the manner shown in Fig. 4, and the spring will allow for a swinging adjustment of the rod in any direction in the manner shown in Fig. 5. The spring will also 50 afford a lateral adjustment of the rod,—in fact a universal one.

Having thus fully described my invention, what I claim as new and wish to secure by Letters Patent of the United States, is— 55

1. The combination with a radius-rod of means for attaching and supporting one or both ends of the rod, said means comprising a volute spring to a coil of which the rod is fastened to move always with the coil. 60

2. The combination with a radius-rod of means for attaching and supporting one or both ends of the rod, said means comprising a volute spring to a coil of which the rod is fastened and a spring-support fastened to a convolution of the spring at the other end of the spring from that to which said rod is fastened. 65

3. The combination with a radius-rod of means for attaching and supporting one or both ends of the rod, said means comprising a volute spring to a coil of which the rod is fastened to move always with the coil, and a pair of bearing members between which the spring is assembled and which limit the 70 lateral displacement of the coils. 75

In witness whereof, I, have hereunto set my hand and seal at Indianapolis, Indiana, this 15th day of April, A. D. one thousand nine hundred and fifteen.

ROBERT H. HASSSLER. [L. S.]
